Attorney.

UNITED STATES PATENT OFFICE.

GEORGE F. EGAN, OF JERSEY CITY, NEW JERSEY.

SEWER CONSTRUCTION.

Original application filed July 31, 1925, Serial No. 47,281. Divided and this application filed April 9, 1926. Serial No. 100,987.

This application relates to improvements in sewer construction and is a division of my similarly entitled co-pending application Serial Number 47,281, filed July 31, 1925.

5 The present application is concerned more particularly with a grating or guard for sewer basins, which will exclude entry to the basin from the gutter of material of a size greater than can pass through the openings 10 in the grating or guard. At the present time material such for instance as sticks, tin cans, and rags, are permitted entry to sewer basins from gutters, and such material renders the cleaning of basins more difficult 15 than would otherwise be the case, and requires the cleaning of basins more frequently than would otherwise be necessary. The expense of cleaning basins is considerable and material permitted to enter basins frequently causes the stoppage of pipes which 20 connect the basin with the sewer.

Another object of my invention is to provide an improved grating or guard which is of unitary construction and provided with 25 automatic catch devices for holding the same in place and resisting the ready removal of the same, for instance by mischievous boys or anyone who might desire to remove the grating or guard to throw objects into the 30 basin.

With the foregoing and other objects in view, the invention will be more fully described hereinafter, and will be more particularly pointed out in the claims appended 35 hereto.

In the drawings, wherein like symbols refer to like or corresponding parts throughout the several views,

40 Figure 1 is a fragmentary perspective view showing a gutter and sidewalk with my improved device in place;

Figure 2 is a vertical section taken on the line 2—2 in Figure 1;

45 Figure 3 is a fragmentary front elevation of a curbing with parts below broken away and with my improved grating or guard shown in elevation;

Figure 4 is a fragmentary top plan view 50 of my improved construction with parts broken away; and

Figure 5 is a vertical section taken on the line 5—5 in Figure 3.

Referring more particularly to the drawings, 24 designates a street or roadway, 25 a curb, and 26 a sidewalk.

55 In Figures 1 and 2 a cover 130 is shown as provided in or on the sidewalk. By raising this cover 130 entrance may be effected to the basin 52 through an opening 131 to remove contents of the basin, to repair the basin, or for any other desired purpose. The opening 131 is shown as made through the sidewalk and as directly above the basin 52. A ladder 55 is shown as provided by which a workman entering through the 60 opening 131 may descend in the basin for the purpose of cleaning out the same or performing any other desired work.

65 A form of grating or guard 36 is shown as fitted in an opening 37 in the curb 25. 70 In this case entry to the basin from the gutter is shown as through the curb opening and is designated as 200. The curb 25, at the sides of the opening 37, is shown as provided with recesses 41 to receive the free outer ends of springs 42, shown as carried by the grating or guard 36, the free ends of the springs being shown as offset backwardly to enable them with greater facility to snap into the recesses 41 in the act of pushing the grating or guard 36 into place.

75 The springs 42 are such as to maintain the grating or guard normally in its place. The grating or guard 36 is shown as provided with an arm 40 on either side. Said arms 80 are intended to assist in holding the grating or guard 36 in place. As the grating or guard 36 rests in the curb, the curb will also assist in holding the grating or guard in place. The curb may be recessed to receive the arms 40 and the sides of the grating or guard 36.

85 The grating or guard itself is made up of an open-work structure. The drawings show the grating or guard as including spaced horizontal bars with short vertical bars extending between the horizontal bars, and with the ends of the upper horizontal bar curved down to the lower horizontal bar and meeting with the lower horizontal bar just inwardly of the arms 40. The opening 37 in the curb is shown as made to correspond with the shape of the grating or guard illustrated in the drawings. It will 90 95 100

be understood, however, that the grating or guard may take other forms.

The springs 42 will automatically snap into the recesses 41 when the grating or guard is pushed into place. These springs will be relatively strong so as to prevent the cover from being readily pulled out.

It is obvious that various changes and modifications may be made in the details of construction and design of the above specifically described embodiment of my invention without departing from the spirit thereof.

What is claimed is:—

1. A sewer construction comprising a curb having an opening to the sewer, and provided with a shouldered socket about the opening and recesses spaced inwardly from the shouldered socket, an open-work guard removably fitted into said shouldered socket, and resilient arms carried by the inner portion of the guard with the free ends offset

backwardly whereby to snap into said recesses.

2. A sewer construction comprising a curb having an opening to the sewer and shouldered socket at the mouth of the opening flush with the curb line, said curb also having recesses substantially square in cross section in the side walls of the opening offset inwardly from said shouldered socket, an open-work guard removably fitted in said shouldered socket flush with the curb line, and spring arms having one end secured to the guard and the other ends bent away from the guard and outwardly beyond the side edges of the guard whereby to encounter the wall of the opening and to snap into said recesses when the guard is put in place.

In testimony whereof I affix my signature.

GEORGE F. EGAN.
